UNITED STATES PATENT OFFICE.

LUDWIG M. DIETERICH, OF NEW BRUNSWICK, NEW JERSEY.

DESIGN FOR A LOUD SPEAKER.

Application filed March 16, 1925. Serial No. 12,733. Term of patent 14 years.

To all whom it may concern:

Be it known that I, LUDWIG M. DIETERICH, a citizen of the United States, and a resident of New Brunswick, in the county of Middlesex and State of New Jersey, have invented a new, original, and ornamental Design for Loud Speakers, of which the following is a specification, reference being had to the accompanying drawing, forming part thereof.

The single figure in the drawing is a perspective view of a loud-speaker illustrative of my new design.

I claim:

The ornamental design for a loud speaker substantially as shown.

LUDWIG M. DIETERICH.
